UNITED STATES PATENT OFFICE.

WILLIAM HAROLD ARMSTRONG, OF PLAINFIELD, NEW JERSEY, ASSIGNOR TO INGER-SOLL-RAND COMPANY, OF JERSEY CITY, NEW JERSEY, A CORPORATION OF NEW JERSEY.

MECHANICAL TIE TAMPER.

Application filed November 19, 1925. Serial No. 69,952.

To all whom it may concern:

Be it known that I, WILLIAM H. ARMSTRONG, a citizen of the United States, and a resident of Plainfield, county of Union, and State of New Jersey, have invented a certain 5 Mechanical Tie Tamper, of which the following is a specification accompanied by drawings.

This invention relates to tamping bars 10 and has for its objects to enable material to be tamped under ties and in similar places with great force.

It is also an object of the invention to enable power to be applied to the tamping bar 15 in a convenient manner. Other objects and advantages of the invention will be in part obvious and in part pointed out hereinafter.

In the drawing in which similar reference characters refer to similar parts,

20 Figure 1 is a perspective view of a tamping bar constructed in accordance with the practice of the invention and shows the manner in which it is employed.

Figure 2 is a perspective view of a modified form of the invention.

Figure 3 is a view in perspective of a second modified form of the invention, and

Figure 4 is a perspective view of the modification shown in Figure 3 indicating the manner of its handling and operation.

Referring to the drawings and more particularly to Figure 1 the tie tamper consists of a bar A having a tamping end B transverse to the length of the bar, a handle C which is adapted to be grasped by the operator and a shoe D pivotally attached by means of a link E to the bar A. The link E is pivoted between two upwardly projecting ears F by means of a pin G and is provided 35 with forked ends H between which the bar A passes and is attached by means of a pin J.

The shoe D is adapted to rest upon a tie K adjacent the tie L which is to be tamped and acts as a brace to bear against as the ballasting material is being thrust under the tie L by the tamping end B. To this end the shoe D is provided with a downwardly extending portion O at right angles to the main body 45 of the shoe by means of which the tie K is gripped.

In operation, the shoe D is placed on a tie such as indicated at K and adjacent the tie L which is to be tamped. The operator grasps

the handles C and, with the pin J as a fulcrum, drives the rock or other ballast material beneath the tie L by means of the tamping end B. For tamping ties which are spaced farther apart or nearer together than normally, extra holes P are provided in the forked ends H of the link E by means of which the distance from the pin J to the pivot G may be suitably lengthened or shortened for convenience in manipulating the handle C. The operator may stand upon the flat portion of the shoe D in order to steady it while tamping.

In the modification shown in Figure 2 a bar Q provided with suitable tamping ends R and a handle S is pivoted directly on a shoe T. A longitudinal slot U is provided in the bar Q which permits sliding movement of the bar on a pin V mounted in a forked projection W of the shoe T. As in the above described embodiment of the invention the shoe T is adapted to rest on the tie K which takes the thrust from the bar Q as the operator presses against the handle S. The operation of this form of invention is similar to that above described. The shoe T is adapted to receive the weight of the operator as he manipulates the tamping end R by means of the handle S. Swinging movement of the bar Q takes place about the pin B as a fulcrum while vertical or longitudinal movement of the bar Q is permitted by the sliding of the pin D in the slot U.

In the embodiment illustrated in Figures 3 and 4 the tamping apparatus comprises a shoe X provided with a link Y pivoted at Z on the shoe X. A bar b is pivotally attached to the forked end c of the link Y and is provided with a handle d at which the force is applied. The end of the bar b is forked as at e and is provided with a pin f to engage a hook-shaped bar g provided with a slot h. The end of the member g is attached by means of links j to the bar d.

Downward pressure against the handle d forces the tamping end k on the hook-shaped member g downwardly so as to be inserted under the tie L as shown in Figure 4. The bar b being pivoted on the links c presses against the hook-shaped member g while pulling against the extreme end of the member g by means of the links j and provides additional leverage to force the tamping end

k under the tie *L*. The form of tamping bar shown in Figures 3 and 4 is relatively compact and provides greater leverage than the forms above described.

5 I claim:

1. A tamping bar comprising a shoe adapted to rest on a tie, and a bar pivotally mounted on said shoe for independent swinging and vertical movements to tamp material under an adjacent tie.

10 2. A tamping apparatus comprising a shoe having angularly disposed portions to grip a tie, and a bar pivotally mounted on said shoe for independent swinging and vertical

movements adapted to tamp material under 15 an adjacent tie.

3. A tamping apparatus comprising a shoe having angularly disposed portions adapted to rest on and grip a tie, a forked extension on said shoe, a link member pivotally mounted on said forked extension and a bar pivotally attached to said link having a handle at one end and a tamping portion on the opposite end.

20 In testimony whereof I have signed this 25 specification.

WILLIAM HAROLD ARMSTRONG.
